UNITED STATES PATENT OFFICE.

EZRA SANGER BUCKNAM, OF PHILADELPHIA, PENNSYLVANIA, ASSIGNOR
TO JOHN A. BRILL, OF PHILADELPHIA, PENNSYLVANIA.

TRUNNION AND SASH-LOCK FOR CARS.

SPECIFICATION forming part of Letters Patent No. 761,355, dated May 31, 1904.

Application filed May 24, 1902. Serial No. 108,773. (No model.)

To all whom it may concern:

Be it known that I, EZRA SANGER BUCKNAM, a citizen of the United States, and a resident of the city and county of Philadelphia, State 5 of Pennsylvania, (and whose post-office address is care of the J. G. Brill Company, in said city,) have invented certain new and useful Improvements in Trunnions and Sash-Locks for Cars, of which the following is a specification.

10 My invention has relation to a combined trunnion and sash-lock for panels or window-sashes adapted to be moved in grooves formed in cars to open or close the same.

Prior to my invention in cars which are 15 convertible or semiconvertible—that is, as to the former, where the side of the car between the posts is adapted to be wholly opened or closed, or as to the latter, partly open or closed—the movable sashes or panels have 20 been adapted to be moved up and down in grooves formed in or upon the sides of the posts or other convenient parts of the car. The sashes have been in prior practice, so far as I know, bodily guided in the groove on the 25 one hand, or, on the other hand, trunnions or pintles have been formed on the sides of the panel or sash which engage a groove and in some instances a compound groove consisting of a wider upper and a narrow base-groove 30 located at the bottom of the wider groove and a panel or sash frame provided with pintles or trunnions, the latter working in the smaller base-groove, the sides of the frame being adapted to move in wholly or partly the upper 35 or wider groove, has been employed. In none of these instances, so far as I know, has there been, on the one hand, any provision made for utilizing these pintles or trunnions as a means for conjointly guiding the panel or sash in the 40 grooves and for locking or supporting the same in their position of elevation or depression, or, on the other hand, has a longitudinally-movable bolt been employed as a sash or panel guide when coöperating with a groove.

45 My invention consists of a sash-lock provided with a pintle or bolt operating as a trunnion, combined with a groove in which the trunnion moves to guide the sash or panel, said pintle or trunnion being adapted to be

operated both longitudinally and transversely 50 of the groove and as to one phase of my invention to engage a depression or equivalent means located in the groove at predetermined points to lock or support the panel or sash at desired points of elevation or depression, or, 55 as to another phase, to free the panel or sash from the groove by sliding the bolt.

My invention therefore resides in the novel construction and combination of parts herein-after described, and further pointed out in the 60 claims.

In the drawings forming part of this specification, Figure 1 is a plan, partly in section, of a portion of a car-sash or window-frame and a post, showing the application of one form of 65 my improvements. Fig. 2 is a front elevation thereof. Fig. 3 is a sectional elevation of a portion of a car side with the sashes removed; and Fig. 4 is a like view with the sashes inserted, showing a form of car construction to 70 which my invention may be employed. Fig. 5 is a side elevation of a sash-frame and a portion of the car-frame, partly in section. Fig. 6 shows a portion of the sash, the sash-lock in side elevation, a portion of the latter being 75 broken away to expose the construction, and a portion of the car-post in section; and Fig. 7 is an edge view of the sash and lock.

I have illustrated my invention in connection with a conventionally-constructed semi- 80 convertible car, and for the purpose of illustration of my invention it is not necessary that the entire means for closing the car side be illustrated, since my invention may be employed either with what is called a "sash-carrying window-glass" or a "base-panel" 85 with any of the car side opening or closing instrumentalities employed in car structures.

In the drawings, 1 illustrates a sash comprising the side bars 2 and top and bottom 90 cross-bars 3 4 and glass 5, and 6 an upper sash similarly formed of side bars and top and bottom cross-bars, (and the two sash-sections may be provided with means for automatically engaging each other and for disengagement from 95 each other while being raised or lowered,) as illustrated in an application for patent filed by Brill and Bucknam on the first day of Feb-

ruary, 1901, Serial No. 45,545, to which cross reference is here made for a suitable construction in which my invention is employed.

At 7 is the side of the car (both sides being 5 constructed alike) comprising the usual outer longitudinal sills 8 and side posts or stanchions 9, extending upwardly from the sill:

The form of car illustrated herein is of the semiconvertible type—that is to say, it has a 10 fixed panel 10 constructed, as desired, extending upwardly along the car side from the sill 8 to the side openings, upon the rail 11 of which the lower sash 1 is adapted to rest.

In the construction illustrated in Figs. 3, 4, 15 5, 6 the posts are provided with a groove (so far as the sashes are concerned) leading from the rail 11 upwardly, as desired, or as recited in said application, and this groove may actually comprise two grooves 12 13, the upper 20 or wider one, 13, and the lower or base groove, 12, or, as in Figs. 1 and 2, a single groove, the counterpart of 12 in Figs. 3, 4, 5, and 6. The upper sash may be provided with trunnions and the upper portion of the lower sash 25 also provided with trunnions 14 on each side bar 2 at the upper corners to engage the groove 12. In the structure herein illustrated I have applied my invention to the lower part of the sash; but its application may be further 30 multiplied.

At 15 is the combined sash-lock and trunnion. It consists in the embodiment herein illustrated of a casing 16, having an extension 17 let into the edge of the sash-bar 2, (and 35 preferably applied at both sides of the sash,) and having its side plate 18 flush with the edge of the sash-bar, the casing having an upward extension 19 secured to the sash-frame and an inward extension 20 secured to the 40 sash-frame and having a hand-pull 21, and the lower extension 22 secured to the base of the sash-frame.

The inside of the casing is provided with an apertured lug 23, projecting from the casing 45 lock-plate 24, and the plate 18 of the inset extension 17 is likewise apertured at 25 to permit a bolt 26 (which constitutes a trunnion or pintle) of the lock to be moved longitudinally in the casing, the plate 18 of the inset 50 and the lug 23 forming a guide therefor. The shank 27 of the bolt is provided with an outwardly-extending dog 28, and between the dog and the lug 23 and around the bolt-shank is a coil-spring 29, adapted to oppose the inward 55 extension of the bolt.

At 30 is a hand-lever pivoted in the casing upon a pin 31 and having a downwardly-extending lug 32. At 33 is a link pivoted in the casing upon the pin 34 and having a tooth 35, 60 adapted to engage the lug 32 on the lever 30, and a tongue 36, adapted to engage the dog 28.

The bolt 26 is adapted and arranged in accordance with one feature of my invention to be moved in against the stress of the spring 65 for a portion only of its length, so that a sub-

stantial portion of the part projecting from the side of the sash will remain in the groove 12 and act as a trunnion for guiding the sash up and down.

Should it be desired to employ my invention 70 in connection with a single groove, as 12, formed flush with the face of the posts, as in Figs. 1 and 2, between which the sash moves, so that the sash can be readily removed or swung in or out, the posts of the lock can be 75 so adjusted that the bolt may be entirely reciprocated free from the groove so as to release the sash from the same. In this way my invention may be utilized as a means for readily attaching or detaching sashes or panels 80 from the sides of the car, since such an application of my invention would only require a multiplication of the sash-locks at the desired points, say, at the four corners, the bolt 26 or bolts (as the case may be) acting always as the 85 guiding means for the sash in the groove 12 (a groove) should it be desired to raise or lower the sash. My invention also contemplates using the bolt 26 conjointly as a guide-trunnion and lock. To accomplish this, I may 90 employ the following construction.

At predetermined points along the groove 12 and in its base depressions 37 are formed, into which the head of the bolt 26 may be projected by the spring 29, so as to lock the sash 95 in its point of adjustment up or down whenever these depressions may be located, and these depressions may be either holes bored in the base of the groove or be formed as a part of the plate 38 let into the base of the 100 groove or otherwise formed, as desired. When used as a combined guide-pintle and lock, the inward projection of the bolt is limited to just sufficient to cause it to free itself from the holes 37 or steps, &c., the spring 29 keeping it 105 pressed outward. As will now be apparent, it will be immaterial whether the side bars of the sash enter within or engage a groove 13, which it may do in some of the structures in 110 which my invention may be employed.

I am aware that it is not new to provide a sash with a lock carrying a longitudinally-movable bolt adapted to engage holes or depressions or steps in the window-frame or car in which latter a groove has been formed to 115 guide the sash up and down; but so far as I know the bolt or locking instrumentality of the lock did or does not enter in the guiding-groove and form the guide for the sash nor conjointly operate both as a sash-guide and as a lock. Viewed in its broad aspect, therefore, my invention is susceptible of considerable modification without departing from the spirit thereof.

Having described my invention, I claim— 125

1. In a car, the combination with side posts having longitudinal grooves therein, of a sash adapted to slide between said posts and provided with fixed and locking pintles adapted at all times to remain in the said grooves and 130

be operated longitudinally thereof, thereby forming guide-bearings for the sash, and means for operating said locking-pintle a limited distance transversely of the sash for unlocking the same.

2. In a car, the combination with side posts having longitudinal grooves therein, of sashes adapted to slide between said posts and provided with fixed pintles at one end thereof engaging said grooves, locking-pintles, mounted on the other end of said sashes, also engaging said grooves and together with said fixed pintles adapted at all times to remain in and be operated longitudinally thereof, forming guide-bearings for said sash, and means for operating said locking-pintles a limited distance transversely of said grooves.

3. In a car, the combination with side posts having longitudinal grooves and depressions at intervals therein, provided with fixed pintles at one end thereof engaging said grooves, locking-pintles, mounted on the other end of said sashes, engaging said grooves and depressions, and together with the fixed pintles adapted at all times to remain in and be operated longitudinally of said grooves, forming guide-bearings for the sash, and means for operating said locking-pintles a limited distance transversely of said grooves and out of engagement with said depressions.

4. In a car, the combination with side posts having longitudinal grooves and depressions located at intervals therein, of sashes adapted to slide between said posts provided with fixed pintles at one end thereof engaging said grooves, spring-operated locking-pintles mounted on the other end of said sashes, projecting in said grooves and normally engaging said depressions, the said fixed and locking-pintles adapted at all times to remain in said grooves, thereby forming guide-bearings for the sashes, and means engaging said locking-pintle for withdrawing the same out of engagement with said depressions.

5. In a car, the combination with the grooved side posts, of sashes adapted to slide between said posts, a casing secured upon said sash, a trunnion or pintle carried by said casing adapted to enter said grooved side posts, a stationary handle upon said casing, and a pivoted lever immediately above said handle adapted to withdraw said trunnion or pintle.

6. In a car the combination with the side posts having grooves provided with depressions located at intervals therein; of sashes adapted to slide between said posts, a casing secured to said sashes, a trunnion or pintle carried by said casing adapted to enter said grooves and depressions, a stationary handle carried by said casing, means normally tending to retain said trunnion in said depression and groove, and a lever located opposite said handle adapted to withdraw said trunnion or pintle from said depression.

7. In a car, the combination with the side

posts having grooves provided with depressions located at intervals therein; of sashes adapted to slide between said posts, a casing secured to each of said sashes, a trunnion or pintle carried by said casing adapted to enter said grooves and depressions, a stationary handle carried by said casing, means normally tending to retain said trunnion in said depression and groove, a lever located opposite said handle, and means interposed between said lever and trunnion or pintle, whereby depression of said lever will withdraw said trunnion or pintle.

8. In a car, the combination with the side posts having grooves provided with depressions located at intervals therein; of sashes adapted to slide between said posts, a casing secured to each of said sashes, a trunnion or pintle carried by said casing adapted to enter said grooves and depressions, a stationary handle carried by said casing, means normally tending to retain said trunnion in said depression and groove, a lever located opposite said handle, and a pivoted link interposed between said lever and trunnion or pintle, whereby depression of said lever will withdraw said trunnion or pintle.

9. In a car, the combination with the grooved side posts; of a sash adapted to fit between each of said posts, a casing carried upon the lower end of said sash, guides formed in said casing, a trunnion slidably mounted in said guides adapted to enter said grooved side posts, a dog mounted upon said trunnion, a spring interposed between said dog and one of said guides, a pivoted link having a dog engaging said dog upon said trunnion, a pivoted lever mounted above said link, a dog carried thereby engaging a second dog upon said link, and a stationary handle carried by said casing opposite said pivoted lever, whereby motion of said lever toward said handle will withdraw said trunnion.

10. In a car, the combination with the side posts defining openings in the sides of the car, and longitudinal grooves formed in the opposing faces of said side posts; of a sash movable freely between the opposing faces of said side posts, and transversely-movable trunnions extending laterally from the edges of said sash and adapted to project into and remain at all times in engagement with said grooves in the side posts to retain said sash between said side posts and to form guides for said sash during the raising and lowering of the same, and depressions formed at intervals in said side posts at the base of said grooves, into which said movable trunnions are adapted to be projected to lock said sash between said posts.

11. In a car, the combination with grooved side posts defining openings in the sides of the car; of sashes adapted to fit between said posts, fixed pintles or trunnions carried upon the upper portion of said sash extending into the

groove in the side post, and a combined pintle and lock carried upon the lower portion of said sash also extending into and at all times in engagement with the grooves of the adjacent side post, and movable a limited distance transversely thereof.

12. In a car, the combination with side posts having grooves provided with depressions located at intervals located therein; of sashes 10 slidably fitted between said posts, fixed trunnions or pintles carried upon the upper portion of said sashes and extending into said grooves, and sliding trunnions carried upon the lower

portion of said sashes adapted to rest in said grooves and depressions, said trunnions or pintles providing guiding means for said sashes when withdrawn from said depressions, and means for withdrawing said sliding trunnions out of engagement with said depressions.

Signed at the city and county of Philadelphia, State of Pennsylvania, this 13th day of March, 1902.

EZRA SANGER BUCKNAM.
